(57) **CLAIM**

The ornamental design for a lawn mower shell as shown and described.

DESCRIPTION

FIG. 1 is a front perspective view of a lawn mower shell, showing our new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top plan view of FIG. 1; and,

FIG. 7 is a bottom plan view of FIG. 1.

The broken lines shown in the drawings are for the purpose of illustrating portions of the lawn mower shell that form no part of the claimed design.

1 Claim, 7 Drawing Sheets
